(57) **CLAIM**

The ornamental design for a heighten cushion, as shown and described.

DESCRIPTION

FIG. 1 is a front view of the heighten cushion showing my new design;

FIG. 2 is a left elevational view thereof;

FIG. 3 is a rear elevational view thereof;

FIG. 4 is a right view thereof;

FIG. 5 is a top view thereof;

FIG. 6 is a bottom view thereof;

FIG. 7 is a front perspective view thereof;

FIG. 8 is a rear perspective view thereof; and,

FIG. 9 is a view of the heighten cushion in use.

The broken lines shown on the drawings are for the purpose of illustration and form no part of the claimed design.
